(57) **CLAIM**

The ornamental design for an automobile, as shown and described.

DESCRIPTION

FIG. 1 is a front and right side perspective view of an automobile showing our new design;

FIG. 2 is a rear and left side perspective view thereof;

FIG. 3 is a right side elevation view thereof;

FIG. 4 is a left side elevation view thereof;

FIG. 5 is a front elevation view thereof; and,

FIG. 6 is a rear elevation view thereof.

The portions of the vehicle shown in broken lines throughout the drawing are for illustrative purposes only and form no part of the claimed design.
